UNITED STATES PATENT OFFICE

TONY DAVID, OF LYON, FRANCE

CIRCULAR WEAVING LOOM

Application filed June 26, 1930, Serial No. 463,999, and in Germany June 28, 1929.

My invention relates to a driving device for shuttles or heddles in circular weaving looms. This device comprises a non-rotating deformable member in cooperation with a rotating solid member which gives the former a shape comprising projections and depressions; these projections and depressions rotate with the solid member.

In a weaving loom using my invention, a first device is used to drive the shuttles. The latter are housed within the successive depressions of the deformable member and they are pushed by the projections through one shed of warp threads. Two other devices are used for driving the heddles; supposing that a taffeta weave is desired, one series of heddles is attached to the deformable member of the first device, the other heddles being attached to the other member and both members are driven in synchronism with the shuttles, the projections of one corresponding with the depressions of the other and with the shuttles to insure the shedding.

In the annexed drawings:

Fig. 1 is a partial plan view of a circular loom according to my invention.

Fig. 2 is a section on line IV—IV of Fig. 1.

Fig. 3 is a fragmental plan view in which only the heddles and their driving mechanism are represented.

Figs. 4 and 5 reproduce portions of respectively Figs. 2 and 3, to an enlarged scale.

Fig. 6 is an enlarged fragmental plan view showing the rear of a shuttle and the connected parts.

The circular weaving loom represented comprises a cylindrical warp, unwound from warp beams, from which the threads rise, the fabric *t* being wound in the upper portions of the loom.

The warp threads *i* and *p* are drawn through the eyes of heddles 1 and 2 respectively. It is assumed that *p* are the even threads and *i* the odd ones. The heddles 1 and 2 are radially arranged (Figs. 2 and 4) into two superposed horizontal planes. The inner ends of the upper heddles 1 are fixed to a flexible endless band 3 and the inner ends of the lower heddles 2 are also fixed to another flexible endless band 4. Bands 3 and

4 are passed over idlers 5 and 6 circularly arranged around the axis of the loom.

These idlers are supported by arms 7 and 7a fixed to an annular member or rim 8, which is integral with rays 8a and a hub 8b keyed on the driving shaft 9 of the loom.

The loom represented comprises fourteen shuttles and fourteen groups of idlers are provided, each group comprising two idlers 5 and two idlers 6. Of course, according to the length of the shuttles and to the diameter of the loom, the number of idlers of each group could be varied.

It will be apparent, from Fig. 2, that to obtain the same angular opening of the warp sheds, the amplitude of the motion of heddles 2 must be somewhat greater than in the case of heddles 1. Idlers 6 are therefore greater in diameter than idlers 5.

It will also readily be understood, from Fig. 3, that the undulations of bands 3 and 4 are in opposition so that for a shuttle *n* the warp threads *i* are exterior, threads *p* being interior, these respective positions being inverted for the next shuttle. With such an arrangement, a taffeta weave is manufactured on the loom.

The shuttles are driven by means of a third endless band 10 which passes over a group of idlers 11 and 12 rotatably supported by arms 13 and 13a fixed to rim 8, idlers 12 being exterior to band 10 and idlers 11 being interior. Band 10 is thus driven a series of V-shaped undulations as clearly shown in Fig. 1, the number of undulations being equal to the number of shuttles, viz. fourteen in the loom represented.

Band 10 is provided with double pins 19 and 20 comprising an exterior pin 19 having a threaded tail driven through the band and on which is screwed a hollow pin 20 having a blind threaded hole.

Pins 19 and 20 fit into circular depressions 21 provided in idlers 11 and 12, and thus maintain band 10 against falling down by gravity (Fig. 4).

Pins 20 are also adapted to cooperate with a cylindrical comb 18 with which they mesh as if they were gear teeth fixed on the periphery of idlers 12 (Fig. 6). Thus band 10 re-

mains substantially stationary during the rotation of the shuttles. As shown, Fig. 4, cam 18 is supported by uprights 22 fixed to the loom frame *b* and located between two successive heddles.

5 Pins 19 are also adapted to contact the rear of the shuttles (such as *n* Fig. 6) through the inner warp shed (*i* in the case of Fig. 6). The rear part of the shuttles is given a concave section which fits with the path of pins 19 around idlers 11 as shown in Fig. 6. During the rotation of idlers 11 around the axis of the loom, the shuttles are thus pushed through the sheds.

10 15 Each shuttle *n* is supported by an annular track formed by radial members 15 and 16 arranged circularly between the heddles. A third circular range of radial members 17 is provided to laterally maintain the upper 20 part of the shuttles (Fig. 2).

25 Of course, the angular position of the groups of idlers 5 and 6 with respect to idlers 11 and 12 is such that the shed is formed in front of a shuttle and is closed at the rear thereof. Each shuttle is provided with a downwardly projecting guide *n* which passes through the two circular ranges of radial members 14 and 15 which form the shuttle track.

30 35 Each band 3, 4 or 10 is formed of a metallic inner band 40 (of steel for instance) coated on both sides with lateral bands 41 of leather. The inner metallic core 40 of bands 3 or 4 has one of its edges provided with small 40 projections terminating into balls 30 and 31 respectively for the bands 3 and 4 (Fig. 4). The inner metallic core 40 of bands 3 or 41 an eye through which is forced a ball 30 or 31. The heddles are thus firmly attached to the bands but may be readily disengaged when necessary.

Some projections of the bands are longer than the other ones so as to project through the balls 30 or 31 as shown at 32 or 33 in Fig. 4 and they cooperate with radial slits 24 and 25 provided in plates 23 fixed to the uprights 22 (Figs. 4 and 5). By such an arrangement, the bands remain free to move radially (the lengths of slits 24 and 25 being sufficient) and they are maintained radially against rotation around the axis of the loom.

45 The outer end of heddles 1 or 2 is provided with an elongated eye 1a or 2a loose on pins 28 and 29 fixed on annular members 26 and 27. These pins form guide for the heddles.

The loom works as an ordinary weaving loom having two heddles frames and a plurality of shuttles working in regular succession.

50 55 It will be observed that by providing other groups of heddles bands such as 3 and 4, the loom could work as an ordinary weaving loom having four, six, eight, etc., heddles frames.

I claim:

60 65 1. A circular weaving loom comprising

warp threads circularly arranged with respect to the loom axis; shuttles cooperating with said warp threads; means to drive said shuttles; heddles adapted to control said warp threads; flexible members to which one end of said heddles is attached; and means to give said members a series of undulations to insure shedding of the warp threads, said means rotating in synchronism with the shuttles.

70 75 2. A circular weaving loom as claimed in claim 1, wherein the flexible members do not rotate with the shuttles.

80 3. A circular weaving loom as claimed in claim 1, wherein the flexible members are in the form of endless inextensible bands.

85 4. A circular weaving loom as claimed in claim 1, wherein the flexible members are in the form of bands having a metallic core coated with leather.

90 95 5. A circular weaving loom as claimed in claim 1, wherein the flexible members are in the form of endless inextensible bands having projections along one of their edges, one end of the heddles being attached to said projections, and some of said projections registering with fixed slits, parallel to the motion of the heddles, said slits and projections cooperating together to maintain said bands against rotation.

100 6. A circular weaving loom as claimed in claim 1, wherein the means adapted to control the shape of the flexible members are in the form of rollers supported by arms rotating with the loom.

105 7. A circular weaving loom comprising warp threads circularly arranged with respect to the loom axis; shuttles adapted to cooperate with said warp threads; a circular track for the shuttles; means to control said warp threads to insure shedding of the same; a flexible member co-axial with the loom; and means to give said member a series of undulations in which the shuttles are inserted, said means being driven by the loom mechanism, whereby the shuttles are pushed on their track around the loom axis.

110 8. A circular weaving loom as claimed in claim 7, wherein the shuttle-driving flexible member does not rotate with the shuttles.

115 9. A circular weaving loom as claimed in claim 7, wherein the shuttle-driving flexible member is in the form of an endless band.

120 10. A circular weaving loom as claimed in claim 7, wherein the shuttle-driving flexible member is in the form of a band having a metallic core coated with leather.

125 11. A circular weaving loom as claimed in claim 7, wherein the shuttle-driving flexible member is a band having pins on its face nearest to the shuttles, said pins being adapted to contact the shuttles through a warp shed.

130 12. A circular weaving loom as claimed in claim 7, wherein the shuttle-driving flexible

member is a band having pins on its face remote to the shuttles, said pins cooperating with a fixed circular comb to hold said band against rotation with the shuttles.

- 5 13. A circular weaving loom as claimed in claim 7, wherein the means adapted to control the shape of the shuttle-driving flexible member are in the form of rollers supported by arms rotating with the loom mechanism.
- 10 10. In testimony thereof I affix my signature.

TONY DAVID.
